STREAM REGULATOR

Thomas P. Newman, Geneva, and Eugene W. Marchand, Maywood, Ill., assignors to Crane Co., Chicago, Ill., a corporation of Illinois

Application October 15, 1930. Serial No. 488,814

2 Claims. (Cl. 59—23)

This invention relates to a stream regulator such as may be used for continuous operation or for intermittent operation, and particularly to a stream regulator that is especially well adapted for use in combination with plumbing fixtures such as in combination with a drinking fountain.

In service of this latter type for instance, it is well recognized that the user is frequently subjected to a gush of water in the face due to inaccurate manipulation of the control valve or to sudden surges in the pressure of the supply line.

The purpose of this invention is to provide a stream or flow regulator which is particularly well adapted to be used in combination with the control valve in the supply line for a plumbing fixture such as a drinking fountain to prevent these sudden surges or spurts of water. It is manifest that a stream regulator having characteristics making it suitable for this purpose may be utilized for many other purposes in combination with many fixtures other than a drinking fountain.

In accordance with this invention a regulator is inserted in the supply to a drinking fountain preferably in combination with a shut-off valve unless the fountain is to flow continuously. The stream regulator includes a valve member and an actuating means therefor which normally holds the valve in open position and yet permits the same to be controlled by the pressure upon the inlet side of the valve and the resultant back pressure or pressure upon the outlet side.

A better understanding of this invention will be had from the following description given in connection with the drawing, in which:

Fig. 1 illustrates a typical installation with a stream regulator constructed in accordance with this invention applied to a drinking fountain in combination with a shut-off valve.

Fig. 2 is a vertical transverse section taken through approximately the center of the regulating valve and showing the valve in full open position.

Fig. 3 is a similar section showing the valve in operative or partially closed position, and

Fig. 4 is a horizontal transverse section taken along 4—4 of Fig. 3.

Referring particularly to Figs. 2, 3 and 4, it will be seen that the stream regulating valve comprises a housing or body 1, having an inlet or high pressure chamber 2, and an outlet or low pressure chamber 3, the two chambers being substantially the same in cross sectional area at the outlet and inlet ends thereof and being separated by a hollow partition composed of upper and

lower walls 4 and 6 connected by an end wall 7. The upper and lower walls are provided with aligned threaded apertures to receive the tubular portion 8 of the shank 9, the latter being enlarged at its upper end to provide a diaphragm chamber 60 bounded by an annular seat upon which rests an imperforate flexible diaphragm 10 which spans the enlarged end of the shank. The diaphragm is clamped in place by the bonnet 11 threaded into the upper end of shank 9. 65

The upper wall of the body of the valve is also formed with an opening to permit the entry of the tubular portion 8. A gasket 12 may be inserted between the shank 9 and the upper wall of housing 1 to provide a leak-proof joint therebetween. 70

The base of the tubular portion 8 is formed with two spaced ports constituting upper and lower vertically aligned ports and with transverse ports 13 and 14 thereabove which establish communication between the inlet and outlet chambers of the valve. 75

Slidably mounted within the bore of the tubular portion 8 is a webbed reciprocating piston valve stem 15 the upper end of which is secured to diaphragm 10. The stem is provided with two annular portions 16 and 17 spaced apart substantially the same distance as the distance between the vertical ports of the shank portion 8 whereby flow therethrough may be controlled. 85

The valve 15 and diaphragm 10 may be given an initial setting by means of a compression spring 21 disposed within the bonnet at the upper end of the valve. The tension of the spring may be adjusted by means of a recessed adjusting screw 22 in which the upper end of the spring sets. The adjustment is preferably such that the valve will never fully close. The screw 22 may be locked in adjusted position by means of a lock-nut 23. Unauthorized adjustment and tampering of the adjusting screw is prevented by means of a cap 24 vented as at 25. The vent 25 in the cap 24 allows air to enter the chamber above the diaphragm so that the action of the restricting piston-valve-stem will not be made sluggish by the air confined in this chamber. 95

The operation of the valve is as follows:

Normally the spring 21 is adjusted to urge valve 15 in a downward or full open position as shown in Fig. 2. Any inflowing liquid entering inlet 2 105 must flow through the valve, that is, between the webs of the stem and through passages 13 and 14 into outlet 3. Should a sudden surge of inlet pressure occur, a back pressure will be built up in outlet 3 and will act upon the lower side of 110

diaphragm 10 and force the valve stem 15 toward its closed position against the action of spring 21. When the pressure on the inlet side of the valve drops, the back pressure will drop accordingly and spring 21 will function to lower the stem 15 and thus increase the opening through the ports 13 and 14 so as to obtain the same flow at the lower pressure.

It has been found that the valve as previously described, does not flutter appreciably but takes a position substantially immediately in accordance with the adjustment of spring 21 and the pressure of the incoming fluid. Any sudden increase in inlet pressure will cause a corresponding increase of pressure against the diaphragm 10, thereby tending to close the valve against the action of the spring 21.

Referring particularly to Fig. 1 there is illustrated a typical fountain installation in which the regulating valve would be subjected to intermittent use. In this illustrated application the regulating valve is shown having its outlet 3 connected to a drinking fountain 26 and its inlet connected to a shut-off valve 27, the latter being connected to any suitable source of supply 28.

In an installation of this character, the valve functions substantially as previously described, that is, if the user operates valve 27 slowly valve 15 will not be moved approximately from the position shown in Fig. 2 and will accordingly permit flow of water through the valve. Should valve 27 be opened too far or suddenly or should the supply line pressure suddenly increase, the sudden flow of water through the regulating valve would act upon the diaphragm 10 to move the valve stem toward its upper position thereby maintaining a substantially constant flow through the regulating valve.

From the above it can be seen that there is provided a stream regulating valve which may be used for either continuous or intermittent service and which when used in drinking fountain service will tend to prevent sudden spurts or gusts of water from the fountain.

Installation of such a stream regulator will also insure a flow at constant pressure even though the supply pressure is temporarily reduced due to abnormal use on the same line or increased due to a raising of the pressure during the occurrence of a fire either of which two con-

ditions frequently occur in certain communities. In other words, the stream regulator valve will permit the use of a drinking fountain on a service where the pressure may vary through a reasonable range.

It is obvious that minor changes may be made in the above invention without departing from the spirit and scope of the invention as defined in the claims appended hereto.

We claim:

1. A regulating valve comprising a valve body provided with an inlet and outlet of substantially equal cross sectional areas, a hollow partition separating said inlet and outlet, a shank member extending through the walls of said partition and being provided with ports leading into said hollow partition and additional ports leading to the outlet side of said valve, a piston valve slideable in said shank and arranged to control the openings through said ports to control the flow of fluid through said valve, said valve permitting restricted flow therethrough when in closed position, a spring for normally urging said piston valve open and a diaphragm operatively connected to said piston valve, said diaphragm being subject to the pressure in the outlet side of the valve.

2. A regulating valve comprising a valve body divided into a high pressure chamber having an inlet and a low pressure chamber having an outlet, a shank member enlarged at its upper end to receive a flexible diaphragm and having a cylindrical projecting portion formed with vertically aligned ports therein, a flexible diaphragm in the enlarged portion of said shank, said diaphragm being subject to the pressure in the outlet side of the valve, a bonnet secured to the enlarged end of said shank to secure said diaphragm therein, a piston stem having spaced annular portions slidably mounted within said cylindrical portion and arranged to control the opening through said ports and being secured at its upper end to said diaphragm, a spring for normally urging said valve stem in open position and an adjusting screw for varying the tension on said spring, said valve being arranged to permit restricted flow therethrough when in closed position.
